UNITED STATES PATENT OFFICE.

MAX ORENSTEIN, OF BERLIN, GERMANY.

DUMPING-CAR FOR STICKY MATERIALS.

No. 901,643.

Specification of Letters Patent.

Patented Oct. 20, 1908.

Application filed May 18, 1908. Serial No. 433,480.

To all whom it may concern:

Be it known that I, MAX ORENSTEIN, a citizen of the German Empire, residing at Berlin, in the Kingdom of Prussia, German Empire, have invented new and useful Improvements in Dumping-Cars for Sticky Materials, of which the following is a specification.

As is well known, it is often exceedingly difficult to dump moist loam, clay, or like sticky material from a car, owing to its adhering to the walls of the car-body. In such cases the tilting of the body being insufficient to dislodge the material, the latter must be shoveled out.

My invention relates to improvements in dumping-cars, whereby such sticky materials can be readily and completely dumped on the car-body being tilted.

The invention is illustrated in the accompanying drawings, in which

Figure 1 is a perspective view of a box-bodied dumping-car provided with my new improvement. Fig. 2 shows the body tilted, in its end position, with the inner tray in the course of sliding down. Fig. 3 is a similar view showing the tray in pendent position, after dumping. Fig. 4 is a perspective view of the trough-shaped body of a dumping-car in erect position. Fig. 5 shows the same tilted, in the end position, in the moment of dumping. Fig. 6 is a like view showing the pendent tray, in the after-dumping position.

Referring to Figs. 1-3, the box-shaped body *a* of the dumping-car is provided with a sliding tray fitting snugly into it. In the particular constructional form of the invention illustrated, the tray comprises a base *d* of about half the width of the bed *a* of the body *a*, a back-wall *b* hinged to the base *d* at *b*¹, and end-walls *e* rigidly secured to the back *b*. This latter is furnished with trunnions *c*, which rest on the top of the end-walls of the body *a*.

On the body *a* being tilted, as shown in Fig. 2, the entire tray with the load to be dumped will naturally slide within the body *a*, the trunnions gliding along the tops of the end-walls of the body *a* on which they rest. During this movement there is thus no motion of the material relatively to the walls of the tray, so that the amount of friction and adhesion to be overcome is very greatly reduced.

During the downward sliding motion of

the tray *d*, the trunnions *c* will strike the tops *f* projecting from the end-walls of the body *a*, whereby the top of the wall *b* will be arrested. The material on the tray, however, will continue to descend, by reason of the inclination of the body *a* and also owing to its inertia; and on account of its adhesion to the base *d*, and of the increased friction due to its own weight, the material will drag the base *d* with it. The tray will thus be opened out, the back *b* swinging on the trunnions *c* and the base *d* turning on the hinges *b*¹, so that the parts *b*, *d* finally assume a substantially perpendicular position. The material having thus no longer any hold will be completely dumped from the car.

Figs. 4-6 illustrate the application of the invention to a dumping-car having a trough-shaped body *g*. In the particular constructive form here illustrated the car-body consists of a single plate, bent so as to present flat front and back walls, located at right-angles to each other, and connected by a curved bed or bottom portion. Into this body there fits a tray, consisting of a base-plate *i*, and a back *h* hinged thereto at *h*¹, and presenting rigid end-walls *k*, which latter, however, may be dispensed with. The back *h* is here shown as being a flat rectangular plate of substantially the same area as the back-wall of the body *g*. The base *i* is of substantially the same length, breadth and curve as the bottom of the body *g*. The back *h* of the tray presents trunnions *l*, which engage in the slots *m* of the guide-bars *n* secured to the top of the body *g*. The slots *m* run parallel with the respective opposite walls of the body *g*.

When the body *g* is tilted, the tray with the material being dumped will slide within the body as shown in Fig. 5, the sliding of the material being essentially facilitated in the manner already explained with reference to Figs. 1-3.

When the trunnions *l* have arrived at the ends of the slots *m* (Fig. 5), the sliding motion of the back *h*, but not of the material in the tray, will be arrested. The material itself will continue to slide down, and owing to its adherence to the base *i*, and to the increased amount of friction due to its weight, it will drag the base *i* along. Since the top of the back *h* is held by the trunnions *l*, the entire back *h* will swing on the latter and the parts *h*, *i* will finally come into the position shown in Fig. 6, the base *i* turning on the

hinge h^1 . Owing to this substantially perpendicular position of the parts, the material no longer finds any hold and will thus be completely dumped out.

5 Having thus described my invention, I claim as new:—

1. In a dumping-car, a tilting body; a tray fitting the latter and sliding therein on tipping of the body; and means on the body 10 for arresting the top part of the tray after it has slid for a certain distance, whereby the tray is caused to swing about its top and dump the material in it, substantially as described.
- 15 2. In a dumping-car, a tilting body; a tray fitting therein and consisting of a base, and a back hinged thereto, said tray sliding in the body on tipping of the latter; and means on said body for arresting the top part of the tray-back after it has slid for a certain distance, whereby the tray-back swings about its top, while the base flaps back on its hinges, whence the material contained in the tray is dumped, substantially as described.
- 20 3. In a dumping-car, a tilting body; a tray fitting therein and consisting of a base, and a back hinged thereto, and presenting 25

trunnions, said tray sliding in the body on tipping of the latter; and means on said body for engaging said trunnions and arresting the top part of the tray-back after it has slid for a certain distance, whereby the tray-back swings on said trunnions, while the base flaps back on its hinges, whence the material contained in the tray is dumped, substantially as described.

4. In a dumping-car, a tilting body; a tray fitting therein and consisting of a base, and a back, presenting rigid end-walls, 40 hinged thereto, said tray sliding in the body on tipping of the latter; and means on said body for arresting the top part of the tray-back after it has slid for a certain distance, whereby the tray-back swings about 45 its top, while the base flaps back on its hinges, whence the material contained in the tray is dumped, substantially as described.

In testimony whereof I have signed my name to this specification in the presence of 50 two subscribing witnesses.

MAX ORENSTEIN.
